UNITED STATES PATENT OFFICE.

HENRY C. MILLER, OF WATERFORD, NEW YORK.

THREAD-TRIMMING AND STOPPING AND STARTING MECHANISM.

Specification of Letters Patent. Patented Nov. 16, 1920.

1,359,414.

Original application filed June 5, 1914, Serial No. 843,801. Patent No. 1,257,912, dated February 26, 1918.
Divided and this application filed January 29, 1918. Serial No. 214,376.

To all whom it may concern:

Be it known that HENRY C. MILLER, a citizen of the United States, residing at Waterford, in the county of Saratoga and State of New York, has invented certain new and useful Improvements in Thread-Trimming and Stopping and Starting Mechanism, of which the following is a specification.

10 This invention relates to improvements in button hole machines, and more particularly to the thread trimming and stopping and starting mechanism, and forms a division of my Patent No. 1,257,912, dated February 26, 1918.

15 The primary object of the invention is the provision of simple and practical means for starting, stopping and controlling certain mechanical elements which operate in sequence in a definite cycle of movement.

20 The invention also comprehends improvements in the details of construction and arrangement of parts which will be herein-after described and particularly pointed 25 out in the claims.

In the drawings:

Figure 1 is a perspective view of a button hole machine equipped with the improvement.

30 Fig. 2 is an enlarged detail plan view showing certain parts to which the improvement is connected.

Fig. 3 is a detail view of an intermediate connection.

35 Fig. 4 is a side elevation, partly in section, of such parts of the machine in normal position as are necessary to understand the present invention.

Fig. 5 is a similar view showing the parts 40 in actuated position.

Similar reference characters denote corresponding parts in the various views of the drawings.

Referring now to these drawings in detail and more particularly to Fig. 1 showing the complete machine in perspective 20 denotes the table or frame of the machine supported on suitable legs 21, adapted to be secured to the floor. The upper rear part 50 of this table carries an auxiliary support 22, upon which is mounted a sewing machine head 23, of any desired type, the one shown being the Reece type.

As this sewing machine specifically forms 55 no part of the present invention it is not be-

lieved to be necessary to describe the detail structure. The machine shown includes a revolving and reciprocating head 26, provided with a needle 27, and co-operating sewing mechanism to reciprocate through 60 an opening 28 (Fig. 2) in the rear central part of a work table 30. A thread 31 is carried thereby which coacts with an under thread 32 and a reinforcing thread 33, mounted in suitable bobbins on the under- 65 side of the table 20.

Associated with the head 23 as shown in Fig. 1 is a start and stop mechanism 35, which may be of any desired type and is, therefore, not shown in detail. It is sufficient to state that a laterally projecting trip 36 is adapted to be engaged by the upper arm of a bell crank lever 37, pivotally mounted at the point 38 and held in normal position by means of a spring 40. The lower arm of this bell crank lever coacts with a stop 41 and is connected by means of a flexible member or chain 42 (Fig. 4) with the free end of a link 43 (Fig. 3), the opposite end of which is mounted on a rod 44 extending 75 fore and aft of the machine in suitable bracket 45. The rear end of this rod is provided with a stop nut 46 to prevent longitudinal movement. Intermediate the ends of the link 43 is connected a second chain 80 47 provided with a take up spring 48, the lower end of which is connected with the rear arm 50 of a double bell crank lever mechanism.

This mechanism as shown perhaps more 90 clearly in Fig. 1, comprises a centrally disposed transverse shaft 51 and front and rear shafts 52 and 53 respectively, and parallel therewith. An upwardly projecting arm 55 from the shaft 51 is connected by 95 means of a link 56 with a suspended treadle or foot lever 57. This lever is pivoted at the point 58 on a bracket 60, mounted upon the table 20, and carries at its lower end a stirrup 61 whereby it may be moved fore 100 and aft from a normal central or intermediate position as shown clearly by dotted lines in Fig. 4.

The forward transverse shaft 52 is connected by means of a chain 62 provided with 105 a compensating spring 63 to a lever 64 mounted upon a boss 65 held in normal position by means of a spring 66. This lever is connected by intermediate mechanism extending rearwardly of the machine below 110

the work table 30 adapted to operate trimmer knives 67 positioned below the opening 28 in the central part of the table 30, through which the stitching needle 27 reciprocates.

From the above described mechanism it will be seen that when the parts are in normal position as shown by full lines A in Fig. 4, the machine is inactive. A movement of the stirrup 61 rearwardly will rock the double bell crank lever mechanism to the positions shown by the dotted lines, C, causing a downward movement of the shaft 53 and intervening mechanism and cause the end of the lever 37 to actuate the starting trip 36 and permit the needle to perform its stitching functions.

As soon as the operator starts the stitching mechanism, pressure on the treadle 61 is removed, and the lever is brought back to its normal position. This movement withdraws the end of the lever 37 from the trip 36, to allow the latter to assume its normal position when the stitching mechanism has completed its cycle of operation. Upon completion of a buttonhole, the lever is drawn forwardly beyond normal position as shown by the dotted line position B, which movement lowers the rod 52, and pulls the chain 62, which actuates the trimmers to sever the thread.

Coöoperating with this mechanism above described is a suitable gage for positively insuring the proper location of the button hole in the exact center of the collar.

This gage generally comprises a lever 70 pivotally mounted intermediate its ends in suitable trunnion 71 carried at the upper end of a bracket 72 which is in turn carried by a hopper 73 supported at its ends by brackets 74 carried by the table 20. The forward end of this lever 70 is connected by means of a flexible link or chain 75 passing through a guide 76, the lower end of which chain is connected to the rod 44. A cotter pin or stop 77 passing through the chain above the guide 76 limits its downward movement. This connection permits the lever to be rocked about its pivotal support 71 as the starting and stopping mechanism is actuated by the foot lever.

The operation and manner of using the machine will appear clear from the above description, but a brief statement thereof is as follows:—

The operator takes a bundle of collars, usually twenty-four, and places them in the hopper 73 and after snipping the binding string takes the top collar and moves it upwardly and rearwardly against the underside of the gage lever 70 until its left hand end coacts with the laterally moving portion 92 of the gage, as clearly shown in Fig. 1. The right hand end of the collar is then moved over the top of the gage lever until

it registers with the left end portion, and is then pulled with a sufficient degree of pressure toward the left to actuate certain trigger mechanism (not shown), permitting the lever 70 to drop to the dotted line position as shown in Fig. 4. This step securely grips and holds the collar and just before or simultaneously with the rearward movement of the foot lever 61 to the position shown by dotted lines C, the slide is moved rearwardly by means of a handle which places the collar in operative position with respect to the needle 27, and the machine starts. Simultaneously with the starting of the machine the presser mechanism 104 drops to hold the collar in position, and the slide is returned to normal position to gage the next collar. On completion of stitching the button hole the foot lever is moved forwardly to normal position which permits the stitching mechanism to stop. Upon further forward movement to the dotted line position B the trimmer 67 is actuated to cut the threads about the collar. The second collar, having previously been gaged, during the stitching operation is immediately moved forward by the slide and the operation repeated. In this manner a great saving of time is accomplished as the stitching of the collar is done automatically while the operator is gaging the next collar. Of course after the collar has been sewed it is thrown to one side and the gage slide carrying the next collar is moved forwardly.

As the stitching mechanism and the trimming mechanism are wholly independent of each other, as clearly shown in the drawings, if the stitches are imperfectly formed, the trimmers need not be operated every time the stitching mechanism is operated.

It is thus seen that the present invention provides a simple and practical machine which is substantially automatic in its operation and permits a much larger output than heretofore accomplished. The mechanism comprises few parts which are relatively cheap to manufacture and install, and in short is believed to accomplish among others, all the objects and advantages set forth.

As many changes could be made in construction of the above device without departing from the scope of the invention it is intended that all matter contained in the above description as shown in the accompanying drawings shall be interpreted as illustrative and not in a limiting sense.

What I claim is:—

1. In combination, stitching mechanism, start and stop mechanism therefor, trimming mechanism, a lever having a normal intermediate position adapted to be moved in one direction to start said stitching mechanism and in the opposite direction from its

- intermediate position to trim the threads of said stitching mechanism, whereby either the stitching mechanism or the trimming mechanism may be operated independently.
- 5 2. In a button hole sewing machine in combination, a work support, a stitching mechanism positioned thereabove, trimmers operatively associated with the stitching mechanism, start and stop mechanism for the stitching mechanism comprising a lever occupying a normal intermediate position adapted to be moved in one direction to start the machine and in the opposite direction to beyond the normal intermediate position to 10 actuate the trimmer independently of the stitching mechanism.
3. In a button hole sewing machine in combination, a work support, stitching mechanism positioned thereabove, a trimmer associated with the stitching mechanism, start and stop mechanism, a lever, intervening mechanism between the lever and the start and stop mechanism for controlling the latter, and a second intervening mechanism between the first mentioned intervening mechanism and the trimming mechanism for actuating the trimmer at a predetermined time with respect to the starting and stopping.
- 20 4. In a button hole sewing machine in combination, an auxiliary table, stitching mechanism mounted at one side thereof and a work support at the other, stop and start mechanism associated with the stitching mechanism, independent means coöperating with the stitching mechanism to complete a buttonhole, a lever, and intervening mechanism between said lever, the start and stop mechanism and the independent means
- 25 5. In a button hole sewing machine in combination, a work support, stitching mechanism positioned thereabove, a trimmer associated with the stitching mechanism, start and stop mechanism, a lever, intervening mechanism between the lever and the start and stop mechanism for controlling the latter, and a second intervening mechanism between the first mentioned intervening mechanism and the trimming mechanism for actuating the trimmer at a predetermined time with respect to the starting and stopping.
- 30 6. In combination, stitching mechanism, trimming mechanism, stop and start mechanism, a lever having a normal intermediate position adapted to be moved in one direction to actuate the start mechanism and in the opposite direction to permit operation of the stop mechanism and actuate the trimming mechanism to trim the thread.
7. In combination, stitching mechanism, trimming mechanism, stop and start mechanism, a lever having a normal intermediate position adapted to be moved in one direction to actuate the start mechanism and in the opposite direction to permit operation of the stop mechanism and permit operation of the trimming mechanism to trim the thread.
- 35 8. In combination, stitch forming mechanism including a trimmer and stop and start mechanism, and operating mechanism therefor normally in an intermediate position and adapted to be moved in one direction to actuate the start mechanism and in the opposite direction to cause independent actuation of the trimmer.
- 40 9. In combination, stitching mechanism, trimming mechanism, stop and start mechanism, a lever having a normal intermediate position adapted to be moved in one direction to actuate the start mechanism and in the opposite direction to permit operation of the stop mechanism and permit operation of the trimming mechanism to trim the thread.
- 45 10. In combination, stitching mechanism, trimming mechanism, stop and start mechanism, a lever having a normal intermediate position adapted to be moved in one direction to actuate the start mechanism and in the opposite direction to permit operation of the stop mechanism and permit operation of the trimming mechanism to trim the thread.
- 50 11. In a button hole sewing machine in combination, an auxiliary table, stitching mechanism mounted at one side thereof and a work support at the other, stop and start mechanism associated with the stitching mechanism, independent means coöperating with the stitching mechanism to complete a buttonhole, a lever, and intervening mechanism between said lever, the start and stop mechanism and the independent means

In testimony whereof I affix my signature.

HENRY C. MILLER.
